[57] CLAIM

The ornamental design for a steam iron sole plate for high nap fabrics or similar article, as shown and described.

DESCRIPTION

FIG. 1 is a bottom perspective view of a steam iron sole plate for high nap fabrics or similar article showing our new design;

FIG. 2 is a top perspective view thereof;

FIG. 3 is a top plan view thereof;

FIG. 4 is a side elevational view, the opposite side being a mirror image thereof;

FIG. 5 is a bottom plan view thereof;

FIG. 6 is a front elevational view thereof; and

FIG. 7 is a rear elevational view thereof.

The broken line showing of a steam iron in FIG. 1 is for illustrative purposes only and forms no part of the claimed design.

Fig. 1.
